TABLE LIGHTER

Victor Skellern, Barlaston, Stoke-on-Trent, England, assignor to Ronson Corporation, Woodbridge, N.J., a corporation of New Jersey, and Josiah Wedgwood & Sons Limited, Barlaston, Stoke-on-Trent, England, a British company

Filed Oct. 5, 1960, Ser. No. 62,384

Claims priority, application Great Britain Apr. 22, 1960

Term of patent 14 years

(Cl. D48—27)

FIG. 1 is a perspective view of a table lighter embodying my new design;

FIG. 2 is an end elevation thereof;

FIG. 3 is an elevational view thereof as seen from the end thereof opposite from that shown in FIG. 2;

FIG. 4 is an elevational view thereof as seen from the side thereof opposite from that shown in FIG. 1;

FIG. 5 is a top plan view thereof; and

FIG. 6 is a bottom plan view thereof.

I claim:

The ornamental design for a table lighter, as shown.
